DEEP WELL DRILLING APPARATUS

Hans Muegge, Chiclayo, Peru

Application October 7, 1933, Serial No. 692,677
In Germany October 29, 1932

18 Claims. (Cl. 255—3)

This invention relates to an apparatus for drilling wells, comprising a rig for guiding the drilling tools and an operating aggregate belonging to the same.

5 The object of the invention is the provision of a device for drilling wells, which permits of the use of a motor drive for actuating the chisels, etc., acting in free fall against the bottom of the well, and of drilling tools, wimble, 10 etc., operated by means of a rotary table, and is also distinguished by its simple construction and the ready form of control.

According to the invention, the cable secured 15 to the drum of the driving aggregate, which is conducted at this point and at the top of the derrick over pulleys or rolls and carries at the end extending into the well a liner or chisel, is subjected in the driving aggregate at a point 20 between two guide rolls situated at the same elevation to the intermittent action, transversely to its direction of movement, of an operating member, which moves the cable to a certain predetermined extent, and then releases the same. The operating member is preferably mounted on 25 a pair of endless chains, and after each revolution is conducted by the same against the tensioned cable, which it then advances for a certain predetermined distance and finally releases owing to its special construction and nature of 30 guiding, so that the cable, following the pull of the drilling tool suspended thereon, runs back freely, the drilling tool then striking in free fall against the bottom of the well.

Additional features of the invention are 35 disclosed by the following description.

A possible form of embodiment of the invention is illustrated in the accompanying drawings, in which

Fig. 1 is an elevational view of the driving 40 aggregate, partly in section.

Fig. 2 is a section according to the line II—II in Fig. 1.

Fig. 3 is a section according to the line III— 45 III in Fig. 2.

Fig. 4 is an elevational view of the speed regulator for the rotary table.

Fig. 5 is a section taken through the centre of the operating member for the cable.

50 Figs. 6 and 7 are front and side views of the derrick.

Fig. 8 is an elevational view of the top of the derrick on enlarged scale.

55 Figs. 9—11 illustrate diagrammatically the erection of the derrick.

Fig. 12 shows the bottom of the derrick with the rotary table,

Fig. 13 a section taken through the centre of a part of the pipe, and

Fig. 14 a detail of the pipe in cross-section.

The driving aggregate is accommodated in a frame 1, and includes a shaft 2 carrying at its one end the belt pulley 3, which is connected by means of a belt 4 with a pulley mounted on the shaft of a suitable motor.

10 The shaft 2 carries a sprocket wheel 5, which is connected by means of the endless chain 6 with a sprocket wheel 8 mounted on the intermediate gear shaft 7. On this shaft there is also provided a pinion 9 meshing with a gear-wheel 12 15 mounted on the shaft 10 of the drum 11.

The shaft 10 is locked, and the drum 11 runs thereon by means of two bushes 13, the lubrication of which takes place with the assistance of a central hollow space 14 in the shaft 10 containing a sufficient store of oil for a relatively long period and capable of being re-filled through an opening closed by means of a screw 15. The bushes 13 are furnished with grooves or 20 bittings, so that the oil may enter without obstruction.

25 The drum 11 is shiftable axially by means of the lever 16, for the purpose of connecting the same either in positive fashion through the medium of a clutch 17 with the gear wheel 12, 30 or with a manually operated worm wheel 19, the object of which will be described later.

The lever 16 is mounted on the fixed shaft 10 by means of a flat thread 20 of relatively large pitch, and is connected firmly with a rod 21 35 located in an axial bore of the shaft 10, this rod being coupled at its inner end by the bolt 22—which projects outwardly through longitudinal slots 23 in the shaft 10—with the casing 24 of a doubled thrust bearing 25, which is surrounded by a cap 26 fitted on the drum 11.

The two cone clutches 17 and 18 are furnished with springs 27 and 28 of equal strength. The drum 11 is connected in positive fashion with the gear wheel 12 constantly rotating on the fixed 45 shaft 10 or with the worm-wheel 19, dependent on the fact as to whether the lever 16 is moved in the one or the other direction. In the neutral position of the lever 16 (Fig. 2) the drum 11, in the opening 29 of which there is secured the 50 inner end of the cable 30, is able to rotate quite freely, so that the cable is accordingly run off in this position of the drum owing to the weight of the drilling tool.

Above the drum 11 a guide roll 33 for the 55

cable 30 is mounted in freely rotatable and shiftable fashion on a shaft 32, which is located at the top of a structure 31 and is situated parallel to the axis of the drum. The cable 30 proceeds downwards from the roll 33 to a roll 35 situated at the level of the drum 11, the said roll 35 being located on a shaft 34 mounted in the frame 1. The cable 30 passes below the roll 35 then proceeds to a roll 37 provided with a strong suspension 36 and mounted in the frame 1, from which point it then passes upwards to a guide roll at the top of the derrick and thence downwards to the drilling tool.

At a point between the two guide rolls 35 and 37 situated at the same elevation there is provided, in accordance with the invention, an operating member engaging intermittently transversely to the cable 30.

In the form of embodiment illustrated in the drawing there are provided a pair of endless chains 42 on sprocket wheels 38, 39, which are disposed, vertically to the cable 30, in pairs above and below the same, and which are mounted on shafts 40 and 41 situated parallel to the cable.

To coaxially disposed joints of the two chains 42 there is secured a bolt 43 carrying a plate 45 furnished with bearing eyes 44, which plate possesses at its lower edge (considered with regard to Fig. 5) two bearing eyes 46 having an elongated boring 47. Owing to this embodiment of the eyes 46, through the borings 47 of which there is passed a bolt also connecting coaxially disposed joints of the two chains 42, it is possible to pass the plate 45 also over the sprocket wheels 38, 39 without obstructing the movement of the chains 42.

At its centre the plate 45 possesses a roll 50 held thereon by means of bolts 49 and preferably having a slightly conical surface 51, which roll acts as operating member and during the movement of the chains 42 is moved repeatedly into engagement with the cable 30.

To ensure that the cable 30 will always remain perfectly steady in the vicinity of the operating member 50 and that vibratory motion thereof at this point will be avoided there is provided for the same a slot guide 52. This slot guide 52 possesses a gradually initiating bend, which up to that point where it is desired that the cable 30 should leave the operating member 50 recedes to the extent of the diameter of the cable from the end face of the operating member 50 rotating in fixed position. In order, for the purpose of preventing unnecessary friction between the cable and the slot, to limit as far as possible the bend 53 of the guide 52, provision may also be made for the operating member 50 to be moved gradually out of the range of the guide 52. This may preferably be accomplished by making the diameter of the lower pair of sprocket wheels 39 smaller than that of the upper socket wheels 38.

The chains 42 carrying the operating member 50 are driven by a worm 54 mounted on the main shaft 2 and meshing with a worm-wheel 55 mounted coaxially with the shaft 41 for the lower sprocket wheels 39, this worm-wheel being fitted on a shaft 56. The shaft 56, considered with regard to Fig. 1, carries on the right the shiftable portion of a cone clutch 57, which may be actuated by means of a hand lever 58 for the purpose of establishing or interrupting the positive connection of the shaft 56 with the shaft 41.

For operating a chisel with the apparatus as

described, at first the clutch 17 between the gear wheel 12 and the drum 11, the drilling tool having been introduced into the well to within a slight distance from the bottom thereof with the gear wheel 12 and the drum 11 coupled together and the cable 30 withdrawn by the operating member 50 almost up to the point of release, is disengaged, and the clutch 18 moved in between the drum 11 and the worm-wheel 19 held by the worm 59. By reason of the large transmission ratio of this worm gear 19, 59 and the thus resulting self-locking properties thereof, the stationary condition of the drum 11 is ensured in the position accorded thereto. The clutch 57, hitherto disengaged, is now moved in by the lever 58, so that the two chains 42 are accordingly operated through the medium of the pulley 3, shaft 2, worm gear 54, 55, shaft 56, shaft 41 and sprocket wheels 39, and move the operating member 50 connected therewith along the path prescribed by the chains. After passing the highest point of its path the operating member 50 moves against the cable 30 retained in position by the slot 52 and carries the same downwards until, following the curvature 53 of the slot 52 and assisted by the conical form of the member 50, the cable slides off the latter, and runs back under the weight of the drilling tool secured to its free end. The drilling tool accordingly strikes with full force against the bottom of the well, and is capable, therefore, of performing its function under the most favorable conditions. Any tendency of the cable 30 to coil is greatly damped by the resilient device 36 provided in conjunction with the final guide roll 37. In order to steady the cable immediately after it runs back, a damping means may also be provided in the tool system itself.

The interposed elevated roll 33 is of particular advantage as regards the steady winding of the cable 30 on the drum 11. The free longitudinal sliding movement of the roll 33 on its shaft 32 permits of close disposal of the cable windings on the drum 11 without obstruction.

When the apparatus has been operating for a certain length of time with the free length of cable as determined by the drum 11, the effectiveness of the tool is decreased in consequence of the increasing depth of the well. For the purpose of re-setting the tool as the well becomes deeper the shaft 60 of the worm 59 engaging with the worm-wheel 19 coupled with the drum 11, which shaft is mounted in bearings 61 on the structure 31, is furnished with a hand-wheel 62 by means of which the length of the cable 30 may be regulated as desired. This adjustment device is distinguished by its particularly simple form of construction and its extreme reliability in operation, as the same permits at any time of adjustment of the length of cable as the drilling operations proceed without the provision of any kind of pawl and ratchet mechanism and with fixed drum 11.

The driving aggregate, which includes the device for the mechanical operation of the tool acting by gravity on the bottom of the well, may also be employed for driving a rotary table for rotary drilling operations. In order to be able also to perform mechanically the wimble operations hitherto conducted by hand, there is provided in accordance with the invention between the belt pulley transmitting the drive to the rotary table and the driving motor a speed regulator, which enables the rate of movement of the

table to be adapted to the particular cutting tool employed.

In deep well drilling operations the diameter of the well is usually relatively large at the commencement, and is then reduced as the work proceeds. At the commencement, therefore, large cutting tools are employed, which owing to their large range also rotate quite slowly, whilst as the well becomes deeper smaller wimbles are selected which, in view of their reduced range, may operate more quickly. It is only after a certain depth has been reached (say, 150 feet) that a change-over is made from cutting tool operations to pure rotary drilling.

For this latter operation it is then necessary to be able to increase the circumferential velocity of the table very considerably.

The regulator furnished in accordance with the invention, which regulator is disposed between the main shaft 2 driven by the motor through the medium of the belt pulley 3 and the shaft 65 transmitting the drive to the rotary table through the medium of the pulley 63 and belt 64, comprises in substance two belt pulleys of known construction, which are regulable in their effective diameter, are connected by means of a wedge belt, and are located on the two shafts 2, 65.

As shown by Figs. 3 and 4, there are mounted on the outer end of the shaft 2 two flat-conical discs 66 having their apices directed towards each other and arranged to be non-rotary but longitudinally shiftable on the shaft 2. There are also mounted on the end of the shaft 65 two similarly constructed flat-conical discs 67, which are also non-rotary but longitudinally shiftable on 65. These two pairs of discs 66 and 67 each forming a belt disk are connected by a wedge belt 68, which fits with its bevelled side faces against the oppositely disposed sides of the disks 66 and 67.

The disks 66 and 67, which are preferably made resilient towards the outside, are connected with each other at their hubs by means of pivotally connected levers 69. These levers 69 are mounted in rotatable fashion at their centres on vertical bolts 70 located on a support 71 secured to the frame 1.

The levers 69 are extended beyond the shaft 2, 50 and carry at their ends guide nuts 72 furnished with left and right hand inner threads and screwed on a spindle acting as turnbuckle 73 and also furnished in its two halves with left and right hand threads. At the middle the spindle 73 possesses a worm-wheel 14 (Fig. 3) engaging with a worm 75 located on a vertical rod 76, which in turn possesses at its upper end a hand-wheel 77. The rod 76 is held by bushes 78, 79, which are provided in a lever mechanism 80 located on the frame 1 (Fig. 4).

In order to vary the transmission ratio between the shaft 2 and the shaft 65, it is sufficient to tighten, for example, the nuts 72 (Fig. 3) in relation to each other through the medium of the rod 76, the worm 75, the worm-wheel 14 and the spindle 73 by rotation of the hand-wheel 77, so that the distance between the disks 66 becomes smaller and the distance between the disks 77 is increased to a similar extent. The belt 68 is accordingly compelled to pass outwards between the disks 66, and to move inwards between the disks 67, so that in the case of the selected example the speed of the shaft 65 is increased.

The preferably pyramidal frame 82 for the rotary table is mounted on a transverse frame 81.

The latter possesses bearing eyes 83, through which there are passed on the left (Fig. 12) a bolt 84 acting as axis of rotation for the outwardly oscillatory table, and on the right a bolt 85 acting as a locking means for the rotary table 5 in the operative position.

The rotary table frame 82, considered with regard to Fig. 12, possesses on the right hand lateral face a loop 86, in which there may be secured the end of a cable 87, which is wound about a drum in the driving aggregate and is passed over a roll at the top of the derrick, so that with the assistance of this cable 87 the rotary table may be folded back. In this manner it is possible to keep the dimensions of a table 15 intended for large cutting tools within small limits.

At the top of the frame 82 there is provided a vertically disposed bush 88, in which is accommodated the extended hub of a horizontally disposed worm-wheel 89. Meshing with 89 is a worm 90 seated on a shaft 91 having at its end the belt pulley 92, which is connected by the belt 64 with the belt pulley 63 situated on the driving aggregate. 25

The screwing together or taking apart of the pipe may also be performed by the rotary table. If the table is required to rotate to the left the belt 64 is merely crossed. In this connection considerable assistance is offered by the regulator 30 66, 67, 68, 69, since more particularly when taking apart, i. e., when the threads are tight, a lower speed and accordingly a greater power of the table may be used initially, and the work completed in a very short time after loosening the threads 35 by using greater speeds.

To avoid long and heavy operating rods the pipe possesses at equal distances apart transverse borings 93, whereby in order to overcome the weakening of the pipe thus caused reinforcing sleeves 94 are welded on at these points. The movement of the pipe takes place merely by means of one single bolt 95 (Fig. 14), which at the same time represents a safety means. The cutting tool or dove-tail chisel may be secured 45 to the pipe by two threaded bolts. If the tool becomes jammed owing to excessive and rapid pull, the sudden occurrence of stones or inattention on the part of the operator, merely the bolt 95 will be broken, so that all fishing operation is 50 done away with. The bored pipe also permits of particularly simple operation upon fitting and removal; retention may be performed in very simple fashion below the table by means of an inserted rod, as indicated in Fig. 12. 55

If the bore pipe, in addition to cutting tool boring, is also to be employed for rotary drilling, i. e., scavenging operations, the borings 93 will preferably be sealed by means of members 96 welded on (Fig. 13), so that the water is unable 60 to pass out of the pipe.

The rotary table in conjunction with the speed indicator may be employed for all known rotary drilling methods, such as cutting tool, dove-tail drill and crown drilling. 65

The derrick 97, which in the known fashion is composed of 4 metal tubes arranged in pyramidal form, is so constructed that the tubes or legs connected together in pairs are pivotally secured to the underside of the top 98 (Figs. 6-8). The right hand pair of tubes 97 (considered with regard to Fig. 8) are pivoted to the top of the derrick by curved arms 99 and the joint 100, whilst the pair of pipes 97 on the left are connected firmly with the top 98. 75

This embodiment permits of erection of the derrick in rapid and reliable fashion.

At the top 98 of the derrick there is provided the guide roll 101 for the cable 30.

In order to facilitate the removal of the heavy drilling tool, the filled liner or the like lifted in the well, the invention makes provision at the top of the derrick 98 for a guide roll 103 suspended in pendulating fashion by means of rods 102, 10, the spindle thereof carrying at its ends two rolls 104. At approximately the level of the rolls 104 there are secured to the left hand tubes 97 of the derrick (considered with regard to Fig. 6) the ends of two cables 105. These cables 105 are conducted from their points of attachment to the rolls 104, passed about the latter, and returned to rolls 106 provided on the same pair of tubes 97, from where they proceed to a drum 107 in the driving aggregate. This drum 107 is freely rotatable on a shaft 108, which receives its motion by means of a sprocket wheel 109, a chain 110 and a sprocket wheel 111 mounted on the main shaft 2, and may be firmly connected therewith by a clutch 112 controlled by means of a lever (not shown).

If, for example, a liner lifted from the well is to be deposited on the bottom of the derrick for emptying purposes, the same must first be removed from the pipe, which is usually situated well above ground. Heretofore it has been necessary to pass a cable about the liner, and to lift out the same with a considerable expenditure of time and labor, and moreover to hold the same in the lifted position until the cable has been let out. By the provision of the guide roll 103 the removal of the tool is greatly facilitated.

Immediately the tool has been lifted to view the clutch 112 is put in, and accordingly by means of the cable (double cable) 105 the guide roll 103 is moved against the drill cable 30. The double cable 105 then draws the roll 103 and accordingly also the cable 30 and the tool suspended thereon laterally from the range of the pipe, so that after disengagement of the clutch 112 and locking of the drum 107 the cable 30 may be let out to such extent by hand with actuation of the hand wheel 62 that the tool, liner or the like moves on to the floor 113 of the derrick and into the box 114 intended for the same.

Although the removing device described in the above operates with considerable advantage, it is sometimes necessary that more particularly the introduction of the tool into the pipe situated well above ground be carefully checked. According to the invention, the derrick is furnished with an elevator 115, the guide lever mechanism of which consists of a few angle irons 116. The elevator 115 possesses on its upper side a roll 117, about which there is placed a cable 118 having its end secured to the top 98 of the derrick, which cable passes over a guide roll 119 and also a second roll 120 at the top 98 of the derrick to a drum 121, which is mounted in the driving aggregate on the shaft 103 and may be connected in positive fashion with this shaft by means of a clutch 122 actuated by a hand lever (not shown). The fact that the elevator 115 may also be used for lifting and lowering the rotary pipe clamp is disclosed by Figs. 6 and 7. The elevator will also be found of particular advantage in the lifting and lowering of the pipe.

Figs. 9, 10 and 11 show the great advantage offered by the lifting device 102, 103 upon the erection of the derrick. The same serves in this case for the initial lifting of the derrick assem-

bled on the flat ground. Hitherto it has been necessary to initially lift the assembled derrick by means of a pulley or hoist secured to a specially constructed mast.

As shown by Fig. 9, the left hand pair of tubes 97 rigidly connected with the crown 98 are pivoted to the floor 113 at 123.

The derrick, assembled on the ground and having the right hand tubes swung outwards, is supported with the right hand edge of the crown or top 98 against a trestle 124. The latter possesses on the right an incline 125, and at its highest point a cable guide roll 126. The ends of the axis of the roller 103 are connected with the double cable 105, and the cable drum 107 is linked up with the drive, so that the roller 103, following the pull of the cable 105, rolls up the incline 125 and lifts the crown 98. The cable 105 is guided in the roll 126 of the trestle 124.

If the top or crown 98 has reached the position shown in Fig. 10, the lower end of the right hand pair of tubes is connected with the free end of a cable 127, which is wound about a drum 128 mounted in the driving aggregate. The drum 128 is mounted on a shaft 129, and may be connected in positive fashion with a gear wheel 131 by means of a clutch 130 controlled by a hand-lever (not shown). The gear wheel 131 meshes with a pinion 132, which is located on a shaft 133 carrying at its end a sprocket wheel 134, which is connected by means of a chain 135 with a sprocket wheel 136 mounted on the main shaft 2.

After the lower ends of the right hand pair of legs have been connected with the cable 127, the clutch 130 of the drum 128 is put in, the same then being driven by the main shaft 2. The operation of the drum 107 for the cable 105 is interrupted by disengaging the clutch 112, and as shown by Fig. 11 the further erection of the derrick is performed solely with the assistance of the cable 127.

The cable 127 may also be employed for operating a pulley or hoist intended for lifting the derrick and mounted on a special mast.

According to Fig. 1, the driving aggregate is furnished at the left, i. e., on the side directed away from the derrick, with a seat 137 for the operator, this seat being adjustable as regards height and spacial disposal. In this manner the operator is able to observe readily and without obstruction from his seat the progress made in the drilling operation, since all levers for the clutches are arranged in front of or near the seat and readily control the single elements of the driving aggregate.

The operation of the device according to the invention is as follows:

It is assumed that operations are being performed with a liner. The empty liner, situated for example in the box 114, is firmly connected with the cable 30 held laterally of the pipe by the roller 103 (Fig. 6). The cable 30, after the drum 11 has been firmly connected with the worm-wheel 19 by means of the engaged clutch 18, is lifted to such extent by manipulation of the hand wheel 62, and accordingly of the worm 59, until the lower edge of the liner is situated to a sufficient extent above the pipe. The double cable 105 is now let out by releasing the clutch 112, so that the roller 104 swings back under the weight of the liner over the mouth of the pipe. In order to prevent damage to the mouth of the pipe by any swinging action on the part of the liner when the same is let into the pipe, a workman is lifted by the elevator 115 up to the level of the mouth 70

of the pipe to control the introduction of the liner into the mouth by hand, whilst the cable 30 is let out gradually by the operator by means of the worm gear 59, 19.

- 5 The lever 16 is now moved into the middle position, and the cable 30 runs out freely under the weight of the tool. When the length of cable run off from the drum approximately corresponds with the depth of the well, the drum 11
10 will be braked, and the cable 30 let out by hand by means of the hand-wheel 62 and the worm gear 59, 19 until the tool is situated merely a slight distance above the bottom of the well. By engagement of the clutch 57 the operating member
15 50 is now actuated in the manner already described through the medium of the chains 42, and operation thus initiated on the bottom of the well by the tool meeting against the same intermittently under the action of gravity.
20 In order to lift the filled liner from the well for emptying purposes, it is merely necessary to move over the lever 16 in such fashion that the drum 11 is coupled with the gear wheel 12. Immediately the tool appears above ground, the drum 11 is again coupled with the worm-wheel 19. The roller 103 is then moved against the cable 30 by engagement of the clutch 112 and operation of the drum 107 by means of the double cable 105, and the roller 103 passed together with the cable and the liner laterally away from the pipe, in accordance with Fig. 6, and held in this position. The liner is then deposited in the manner already described on the bottom of the derrick in the box 114 and emptied.
25 30 35 If at the commencement drilling is performed with cutting tools, there is employed the rotary table according to Fig. 12 with the speed regulator according to Figs. 3 and 4. For the size of cutting tool at first used the rotary table should perform only very few revolutions per minute, and the regulator is accordingly provided with the adjustment of the disks 66, 67 shown in Fig. 4. As the drilling operation proceeds cutting tools of smaller diameter are employed, which may also be operated at a higher speed.
40 45 For the purpose of exchanging the cutting tools the rotary table requires to be folded back (Fig. 12). To do this the cable 87 is connected with the eye 86 of the rotary table frame 82, and the bolt 85 withdrawn from the eyes 83. The cable is then lifted by the drum intended for the withdrawal device, and the rotary table together with the frame thus swung back about the bolt 84, so that the cutting tool previously in use is exposed, and may be lifted out of the well, for example by means of the cable 30, whereupon the next cutting tool of smaller diameter is introduced into the well and the rotary table moved back and connected with the same.
50 55 60 65 66 In order now to obtain a greater speed in respect of the new wimble fitted, the hand wheel 77 is rotated towards the left, so that the ends of the lever 69 carrying the guide nuts 72 (Fig. 3) of the spindle 73 are approached towards each other. The effective diameter of the disk 66 is accordingly larger, and the diameter of the disk 67 simultaneously reduced to the same extent, so that the transmission ratio has been varied in the desired fashion.
70 75 If it is desired to perform drilling beyond a certain depth (approximately 150 feet), operations are continued either with chisels acting under gravity or rotary drills.
76 In the former case there is employed the op-

erating member for the cable 30, whilst in the latter case the rotary table drill is used. In rotary drilling the table may be run at a higher speed than for cutting tools and the regulator 66, 67, 68 will then preferably be so adjusted that the disk 66 is furnished with its greatest diameter, and the disk 67 with its smallest effective diameter.

In rotary drilling operations there is employed the pipe shown in Fig. 13 having sealed transverse borings. 10

The device according to the invention represents an extremely simple machine for the operation of the tools in the production of deep wells (water wells, oil wells, etc.), and the manufacturing and running costs of the same may be kept at a relatively low figure. 15

There is also provided the possibility of uniting the drive both for the mechanical gravity operation according to the invention as well as for 20 rotary drilling operations and finally for all auxiliary machines in the production of wells in a small machine unit.

What I claim as new and desire to secure by Letters Patent is: 25

1. In a deep well drilling apparatus, a derrick for guiding the cutting tool, a driving aggregate in association therewith, a drum to the said driving aggregate, a cable connecting the said tool with the said drum, guide rolls for guiding the said cable including two guide rolls situated at the same level, an operating member acting vertically on the said cable at a point between the said two guide rolls, and sprocket wheels and endless chains disposed transversely to the said cable 35 for supporting the said operating member.

2. In a deep well drilling apparatus, a derrick for guiding the cutting tool, a driving aggregate in association therewith, a drum to the said driving aggregate, a cable connecting the said tool with the said drum, guide rolls for guiding the said cable including two guide rolls situated at the same level, an operating member acting vertically on the said cable at a point between the said two guide rolls, a worm wheel driven by the main shaft of the driving aggregate, sprocket wheels and endless chains disposed transversely to the said cable for supporting the said operating member, and a disengageable clutch connecting one of the said sprocket wheels with the shaft of the 50 said worm wheel.

3. In a deep well drilling apparatus, a derrick for guiding the cutting tool, a driving aggregate in association therewith, a drum to the said driving aggregate, a cable connecting the said tool with the said drum, guide rolls for guiding the said cable including two guide rolls situated at the same level, an operating member acting vertically on the said cable at a point between the said two guide rolls, sprocket wheels and 60 endless chains disposed transversely to the said cable, and a plate carried by oppositely disposed points of the said chains and supporting the said operating member.

4. In a deep well drilling apparatus, a derrick for guiding the cutting tool, a driving aggregate in association therewith, a drum to the said driving aggregate, a cable connecting the said tool with the said drum, guide rolls for guiding the said cable including two guide rolls situated at the same level, an operating member acting vertically on the said cable at a point between the said two guide rolls, sprocket wheels and endless chains disposed transversely to the said cable, bolts connecting oppositely disposed joints of the said 75

chains, and a plate supporting the said operating member mounted to be oscillatory on the said bolts.

5. In a deep well drilling apparatus, a derrick 5 for guiding the cutting tool, a driving aggregate in association therewith, a drum to the said driving aggregate, a cable connecting the said tool with the said drum, guide rolls for guiding the said cable including two guide rolls situated at the 10 same level, an operating member acting vertically on the said cable at a point between the said two guide rolls, sprocket wheels and endless chains disposed transversely to the said cable, bolts connecting oppositely disposed joints of the said 15 chains, a plate supporting the said operating member, and bearing eyes on the said plate mounted in resilient fashion on the said bolts.

6. In a deep well drilling apparatus, a derrick 20 for guiding the cutting tool, a driving aggregate in association therewith, a drum to the said driving aggregate, a cable connecting the said tool with the said drum, guide rolls for guiding the said cable including two guide rolls situated at the same level, an operating member acting vertically 25 on the said cable at a point between the said two guide rolls, sprocket wheels and endless chains disposed transversely to the said cable, bolts connecting oppositely disposed joints of the said chains, and a plate supporting the said operating 30 member having circular bores and one pair of longitudinal bores in which the said bolts are capable of transverse displacement.

7. In a deep well drilling apparatus, a derrick 35 for guiding the cutting tool, a driving aggregate in association therewith, a drum to the said driving aggregate, a cable connecting the said tool with the said drum, guide rolls for guiding the said cable including two guide rolls situated at the same level, an operating member acting vertically 40 on the said cable at a point between the said two guide rolls, sprocket wheels and endless chains disposed transversely to the said cable, a plate carried by the said chains supporting the said operating member, the said operating member 45 engaging the said cable to move it over a predetermined distance and then release it automatically to allow the said tool to act in free fall against the bottom of the well.

8. In a deep well drilling apparatus, a derrick 50 for guiding the cutting tool, a driving aggregate in association therewith, a drum to the said driving aggregate, a cable connecting the said tool with the said drum, guide rolls for guiding the said cable including two guide rolls situated at the 55 same level, an operating member comprising a roll and acting vertically on the said cable at a point between the said two guide rolls, sprocket wheels and endless chains disposed transversely to the said cable, a plate carried by the said chains, and a bolt on the said plate carrying the said 60 operating member.

9. In a deep well drilling apparatus, a derrick 65 for guiding the cutting tool, a driving aggregate in association therewith, a drum to the said driving aggregate, a cable connecting the said tool with the said drum, guide rolls for guiding the said cable including two guide rolls situated at the same level, an operating member comprising a roll having a slightly conical jacket and acting vertically 70 on the said cable at a point between the said two guide rolls, sprocket wheels and endless chains disposed transversely to the said cable, and a plate carried by the said chains supporting the said operating member.

75 10. In a deep well drilling apparatus, a derrick

for guiding the cutting tool, a driving aggregate in association therewith, a drum to the said driving aggregate, a cable connecting the said tool with the said drum, guide rolls for guiding the said cable including two guide rolls situated at the 5 same level, an operating member acting vertically on the said cable at a point between the said two guide rolls, sprocket wheels and endless chains disposed transversely to the said cable, and a slot guide for the said cable opposite the one length 10 of the said chains.

11. In a deep well drilling apparatus, a derrick 15 for guiding the cutting tool, a driving aggregate in association therewith, a drum to the said driving aggregate, a cable connecting the said tool with the said drum, guide rolls for guiding the said cable including two guide rolls situated at the same level, an operating member acting vertically on the said cable at a point between the 20 said two guide rolls, sprocket wheels and endless chains disposed transversely to the said cable, and opposite the one length of the said chains a slot guide for the said cable having a slight curvature conducting the cable away from the said 25 operating member.

12. In a deep well drilling apparatus, a derrick 30 for guiding the cutting tool, a driving aggregate in association therewith, a drum to the said driving aggregate, a cable connecting the said tool with the said drum, guide rolls for guiding the said cable including two guide rolls situated at the same level, an operating member acting vertically on the said cable at a point between the 35 said two guide rolls, sprocket wheels and endless chains disposed transversely to the said cable, and a slot guide for the said cable opposite the one length of the said chains, the oppositely disposed parts of the said chain length and the said 40 guide being arranged slightly to diverge.

13. In a deep well drilling apparatus, a derrick 45 for guiding the cutting tool, a driving aggregate in association therewith, a drum to the said driving aggregate, a cable connecting the said tool with the said drum, guide rolls for guiding the said cable including two guide rolls situated at the same level, an operating member acting vertically 50 on the said cable at a point between the said two guide rolls, and a separately mounted roller for the cable situated between the said drum and the one of the said two guide rolls situated next to the said operating member, the 55 said operating member engaging the said cable to move it over a predetermined distance and then release it automatically to allow the said tool to act in free fall against the bottom of the well.

14. In a deep well drilling apparatus, a derrick 60 for guiding the cutting tool, a driving aggregate in association therewith, a drum to the said driving aggregate, a cable connecting the said tool with the said drum, guide rolls for guiding the said cable including two guide rolls situated at the same level, an operating member acting vertically 65 on the said cable at a point between the said two guide rolls, a fixed shaft, and a freely rotatable and freely shiftable roller for the cable mounted on the said shaft and situated between the said drum and the one of the said two guide rolls situated next to the said operating member.

15. In a deep well drilling apparatus, a derrick 70 for guiding the cutting tool, a driving aggregate in association therewith, a drum to the said driving aggregate, a cable connecting the said tool with the said drum, guide rolls for guiding the 75

- 5 said cable including two guide rolls situated at the same level, an operating member acting vertically on the said cable at a point between the said two guide rolls, a worm wheel mounted on the shaft of the said drum, a releasable clutch connecting the said drum and the said worm wheel, and a manually operable worm of small diameter meshing with the said worm wheel.
- 10 16. In a deep well drilling apparatus, a derrick for guiding the cutting tool, a driving aggregate in association therewith, a drum to the said driving aggregate, a cable connecting the said tool with the said drum, guide rolls for guiding the said cable including two guide rolls situated at 15 the same level, an operating member acting vertically on the said cable at a point between the said two guide rolls, a worm gear of large transmission ratio for letting out the cable mounted on the shaft of the said drum, and a releasable clutch connecting the said drum and the said worm gear.
- 20 17. In a deep well drilling apparatus, a derrick for guiding the cutting tool, a driving aggregate in association therewith, a drum to the said driving aggregate, a cable connecting the said tool

with the said drum, guide rolls for guiding the said cable including two guide rolls situated at the same level, an operating member acting vertically on the said cable at a point between the said two guide rolls, rods situated at the crown of the derrick and a pendulating guide roller mounted on the said rods for lifting the tool from the well. 5

18. In a deep well drilling apparatus, a derrick for guiding the cutting tool, a driving aggregate 10 in association therewith, a drum to the said driving aggregate, a cable connecting the said tool with the said drum, guide rolls for guiding the said cable including two guide rolls situated at the same level, an operating member acting vertically 15 on the said cable at a point between the said two guide rolls to move the said cable a predetermined distance and then release it automatically to allow the said tool to act in free fall against the bottom of the well, and a rotary table 20 to permit of rotary drilling operations after a certain depth of the well has been reached.

HANS MUEGGE.
